UNITED STATES PATENT OFFICE.

ARNOLD GROB, OF CLEVELAND, OHIO, ASSIGNOR TO THE HYDRAULIC PRESSED STEEL COMPANY, OF CLEVELAND, OHIO, A CORPORATION OF OHIO.

APPARATUS FOR PRODUCING PRESSED-METAL ARTICLES.

1,345,594.

Specification of Letter's Patent.

Patented July 6, 1920.

Original application filed December 30, 1912, Serial No. 739,194. Divided and this application filed October 27, 1917. Serial No. 198,767.

To all whom it may concern:

Be it known that I, ARNOLD GROB, a citizen of the United States, residing at Cleveland, in the county of Cuyahoga and State of Ohio, have invented a certain new and useful Improvement in Apparatus for Producing Pressed-Metal Articles, of which the following is a full, clear, and exact description, reference being had to the accompanying drawings.

This invention relates to an apparatus for producing metal articles, such as cans, barrels and other receptacles, and is particularly adapted for the production from pressed metal of articles of this kind having a greater diameter intermediate of the ends than at the ends thereof. The invention illustrated, described and explained herein is a division of my application No. 739194 filed December 30, 1912. As articles of this character referred to have been constructed heretofore, it has been deemed necessary to produce this bilge or intermediate enlargement either by bringing down the metal from the top or upwardly from the bottom of the blank to provide for the enlargement, or by stretching the metal at such intermediate portion. Both of these operations necessitate the application of very great force to the metal, requiring heavy and expensive machinery; a more serious detriment, however, to these processes results from the strain to which the metal is subjected, said strain thinning and weakening the metal and rendering it less capable of withstanding the incidents of use than if it were not so mistreated. For convenience of description, the metal from which the article is to be formed will be referred to as "a blank" at any stage prior to the operation which gives it the final bilged shape. In the practice of my invention, the blank is made of a diameter equal, or substantially equal, to the greatest diameter of the finished article, and this blank is then subjected to the action of my apparatus which operates to elongate the blank and reduce the diameter thereof where desirable (in the case of a barrel, at the ends) and to provide sufficient metal in any transverse plane to allow the blank, by being merely expanded, to attain the desired shape and cross sectional area without materially stretching the metal. That is to say, by the peculiar

manner of operating upon the blank, sufficient metal is provided between the ends of the blank—at the place where needed—to enable the blank to be given the shape which exists in the finished article by merely expanding certain portions of the blank without stretching or drawing the metal to any material extent and hence without diminishing the strength thereof materially.

In producing the article, I preferably make use of the mechanism illustrated herein for the purpose of producing an article in the manner described. In the drawings forming part hereof, Figure 1 represents a perspective view of a blank produced by my apparatus, the blank being of the form which it assumes prior to the last or expanding operation; Fig. 2 represents the same blank prior to being subjected to the operation by which the form shown in the preceding figure is produced; Fig. 3 is a longitudinal sectional view through a machine or apparatus for producing the blank shown in Fig. 1, the blank of Fig. 2 being shown in place; Fig. 4 represents a similar view showing the positions of the parts while the blank is being operated upon; Fig. 5 is a transverse sectional view taken through the rollers 9—9, the parts being shown in the positions which they occupy in Fig. 4; Fig. 6 a sectional view through the central part of the blank shown in Fig. 1; and Fig. 7 a detail in plan of the machine or apparatus shown in Figs. 3 and 4, the movable dies being omitted.

Describing the various parts illustrated herein by the use of reference characters, 1 denotes the vertically reciprocal frame of a die press, said frame carrying a plunger 2 and having pivoted thereto a plurality of downwardly extending arms 3, the purpose of which will be disclosed hereinafter. These arms and the plunger pass through a stationary intermediate frame member 4, openings being provided for such plunger and for the arms, the openings for the arms being laterally elongated, as shown at 5, to permit the arms to swing upon their pivotal supports.

6 denotes a stationary tubular member having an internal diameter at least as great as the maximum diameter of the blank. The member 6 is provided with upwardly and outwardly projecting arms 7, four pairs

of such arms being shown. These arms extend upwardly, preferably to the top of the tubular member 6, and each pair of arms supports at their upper ends a shaft 8 on which there is mounted a roller 9. The arms 3 are adapted to pass between the rollers 9 and the tubular member 6. The member 6 is provided at its upper end with an upwardly extending flange 6^a and is slotted below the top thereof to provide guides for a plurality of movable dies 10, there being one movable die for each arm 3 and roller 9. Each of these movable dies 10 is wedge-shaped in cross section, having its upwardly flared sides 11 supported on the reversely flared or inclined sides 12 of segmental fixed dies 13 (see Figs. 3 and 7). The outer ends of the dies 10 are adapted to bear against the inner edges or faces of the arms 3, the outer faces or edges of such arms bearing against rollers 9, the inner edges or faces of said arms being concavely recessed, as shown at 14, for purposes described hereinafter. By reference to Figs. 5 and 7, it will be seen that the inner edges 13^a of the fixed dies are rounded off downwardly and outwardly whereby, as the movable dies are retracted, the blank will be drawn along an extended rounded edge, thereby to prevent the cutting or rupturing of the metal.

15 denotes a tubular support projecting downwardly from the stationary member 4 and into the upper end of the tubular member 6. The cylindrical blank *a* is fitted over the support, with its lower end above the die members 10 and 13. This blank, prior to being operated upon by the mechanism described herein, is of a diameter equal to the greatest diameter of the article which 40 it is desired to produce. The inner edges of the dies 10 and 13, when the parts are in the position shown in Fig. 3, form a circle the diameter of which is substantially equal to the end diameter which it is desired the 45 blank shall have after such operation. As shown, this diameter is only sufficiently greater than the diameter of the plunger 2 to enable the metal of the blank *a* to be received conveniently between the plunger 50 and the inner edges of the dies. With the parts arranged as described, the member 1 is moved downwardly by the mechanism usually employed in die presses, carrying the plunger 2 with it, and this plunger strips 55 the blank *a* from its support 15 and forces the blank downwardly within the tubular member 6 and across the inner edges of the dies 10 and 13. With the parts constructed as shown, the lower end of the blank will 60 be a circle of substantially the same diameter as the plunger 2. As the plunger descends the blank presses against the inner edges of the dies and the dies 10, being movable, will be pressed outwardly against 65 the arms 3, which arms will serve as profilers

to control the movement of these dies through the engagement of the outer edges 14 with the rollers 9. The dies 10 are permitted to move outwardly until the middle points of the concave edges 14 bear against 70 said dies, after which further downward movement of the plunger will cause the dies 10 to be forced inwardly by the concave edges 14 until at the end of the downward stroke of the plunger the upper end 75 of the blank will be contracted to substantially the diameter of the plunger, as may be readily seen from an inspection of Figs. 1 and 4. By the operation of the mechanism as described, the blank *a* has been reduced to a minimum diameter at its ends, but the cross sectional area increases gradually from each end toward the center. Those portions of the blank which have been operating against the dies 10 will form 80 outwardly projecting segments *b* and the portions of the blank intermediate of such segments and which have been operated upon by the fixed dies 13 will form cylindrical segments *c*. With the contour given to the 85 inner curved edges 14 of the arms 3, the segments *b* will be of true bilge form, said segments having their greatest amount of projection at the longitudinal center of the blank.

Owing to the manner of constructing the dies and the operation of the same upon the blank, the linear extent of any inwardly directed portion *c*, *d* of the blank between two of the outwardly projecting segments 100 *b* will be equal to or substantially equal to the linear extent of an arc *e* of the circle continuing and joining said segments *b* and having the same center of curvature as said segments. This is true for any transverse 105 section that may be taken through the blank. As a result, the inwardly projecting portions *c*, *d* of the blank may be pressed or expanded outwardly to form a symmetrical continuation of the segments *b* without 110 materially stretching the metal or subjecting it to any other strain than that necessary merely to move it, without material stretching, from one position to another. This expanding or pressing outwardly of the indentations may be accomplished by any approved mechanism including the well-known expanding dies or rollers, and hence illustration of such expanding mechanism is believed to be unnecessary.

While the construction shown herein is designed for the production of an article of the general shape of a bilged barrel, it will be obvious that varying shapes may be given to the blank and to the article to 125 be produced therefrom by suitably varying the proportions of parts (and particularly the curvature of the edges 14 of the arms or profilers 3), as conditions may demand. By the apparatus disclosed herein, it will 130

be evident that an article may be produced having an expanded portion between its ends without, on the one hand, the necessity for bringing down the metal from the ends 5 of the blank to the middle or enlarged portion and without, on the other hand, materially stretching the intermediate portion of the blank to accommodate the increased dimensions at this point.

10 While I have shown herein a blank of cylindrical form which is subjected to the operations whereby a finished article having an enlarged intermediate section may be produced, I do not intend to be limited to 15 this particular shape, except as such limitation may be included positively in the claims hereto annexed. For certain purposes, it may be advisable to use a blank which is rectangular or polygonal in section.

20 Having thus described my invention what I claim is—

1. In an apparatus of the character described, the combination of a movable die member, a blank support, means for causing 25 relative movement between said die member and said blank support, and means for moving the said die member, the last mentioned means comprising a profiler having oppositely inclined portions controlling the movement 30 of the die member toward and from the support.

2. In an apparatus of the character described, the combination of a series of movable die members, a blank support, means 35 for causing relative movement between said die members and said blank support, and means for moving the said die members, the last mentioned means comprising profilers each having oppositely inclined portions 40 controlling the movement of the die members toward and from the support.

3. In an apparatus of the character described, the combination of an annular series 45 of die members, a blank support, means for causing relative movement between the said members and the blank support, and means controlled by such movement for moving the die members inwardly and permitting them to yield outwardly, the last mentioned means 50 comprising profilers each having oppositely inclined portions, and rollers engaging said profilers.

4. In an apparatus of the character described, the combination of a series of die 55 members, a blank support, means for causing relative movement between the said members and the blank support, and means controlled by such movement for moving the die members toward and from the support, 60 the last mentioned means comprising profilers each having oppositely inclined portions, and anti-friction devices coöperating with said profilers.

5. In an apparatus of the character described, the combination of a series of fixed

and movable die members, a blank support, means for causing relative movement between said die members and said blank support, and means controlled by such movement for permitting the movable die members to move outwardly and for moving the same inwardly, the last mentioned means comprising profilers each having oppositely inclined portions adapted to engage the movable die members, and anti-friction 75 means retaining said profilers in operative relation to said movable die members.

6. In an apparatus of the character described, the combination of an annular series of fixed and movable die members, a blank support, means for causing relative movement between said die members and said blank support, and means controlled by such movement for moving the movable die members toward and from the support, the last mentioned means comprising profilers having curved portions adapted to engage the movable die members, and anti-friction means retaining said profilers in operative relation to said movable die members. 90

7. In an apparatus for making articles of the character set forth, the combination of a series of alternating fixed and movable dies, a plunger, means for moving said plunger through the central opening of said dies, and means coöperating with the movable dies to cause the same to move gradually inwardly and permit the same to move gradually outwardly during the movement of the plunger. 100

8. In an apparatus of the character set forth, the combination of an annular series of fixed and radially movable dies, a blank holder movable through the interior of said dies, and means movable with the blank holder and engaging the movable dies to variably limit the outward movement thereof. 105

9. In an apparatus of the character set forth, the combination of a series of fixed and movable dies, a plunger movable through the interior of said dies, rollers opposite the outer edges of the movable dies, and profilers interposed between the rollers and the movable dies and movable with said plunger, said profilers each having oppositely inclined edges for controlling the movement of the movable dies. 110

10. In an apparatus of the character set forth, the combination of an annular series of fixed and movable dies, means for moving a blank across the inner edges of said dies, the fixed dies having downwardly and inwardly inclined sides forming guides for the movable dies and having rounded inner curved side edges, and means for causing said movable dies to traverse their respective guides. 115

11. In an apparatus of the character set forth, the combination of an annular series of fixed and movable dies, the fixed dies hav- 120

ing downwardly and inclined sides forming guides for the movable dies and the inner edges of said fixed dies being rounded off downwardly and outwardly, a blank holder, 5 means for moving such holder across the inner edges of the fixed and movable dies, and means controlled by the movement of

such blank holder for moving the movable dies inwardly and permitting the same to move outwardly along their guides.

10 In testimony whereof, I hereunto affix my signature.

ARNOLD GROB.
